(57) **CLAIM**

The ornamental design for a bottle, as shown and described.

DESCRIPTION

FIG. 1 is a perspective view of a bottle showing our new design;

FIG. 2 is a side elevational view of the bottle of FIG. 1;

FIG. 3 is a side elevational view of the bottle rotated 180 degrees from the view of FIG. 2;

FIG. 4 is a side elevational view of the bottle rotated 90 degrees from the view of FIG. 3;

FIG. 5 is a side elevational view of the bottle rotated 180 degrees from the view of FIG. 4;

FIG. 6 is a bottom plan view of the bottle; and,

FIG. 7 is a top plan view of the bottle.

The broken lines represent the portions of the design that form no part of the claim.
